UNITED STATES PATENT OFFICE

164,572

COASTER

Arthur H. Happe, Detroit, Mich.

Application April 22, 1950, Serial No. 9,426

Term of patent 14 years

(Cl. D44—10)

To all whom it may concern:

Be it known that I, Arthur H. Happe, a citizen of the United States, residing at Detroit, in the county of Wayne and State of Michigan, have invented a new, original, and ornamental Design for a Coaster, of which the following is a specification, reference being had to the accompanying drawing, forming part thereof.

Fig. 1 is a side elevational view of a coaster showing my new design; and

Fig. 2 is a top plan view thereof.

I claim:

The ornamental design for a coaster, as shown.

ARTHUR H. HAPPE.
